UNITED STATES PATENT OFFICE

2,507,333

CLOSURE FOR MUFFLERS

Dallas J. Coursey, Chicago, Ill.

Application March 7, 1947, Serial No. 733,108

1 Claim. (Cl. 2-91)

2

1 My invention relates to mufflers or scarfs worn around the neck, and more particularly to the frontal closures thereof, and one of my objects is to provide a novel closure in conjunction with slide fastening means employed for articles of this type.

A further object is to construct the muffler with a frontal formation which places the cloth of the muffler edge-to-edge along the line of the closure, so as to fully conceal the slide fastener located therein.

Another object is to form the cloth of the muffler in a manner to provide several plies in the frontal zone, such plies being fastened together and closed to form a firm front and additional protection against cold and other weather conditions.

An additional object is to form the cloth of the muffler with a pair of vertical pockets in which the cloth base of the slide fastener are firmly lodged and secured.

An important object is to design a muffler of the above character which presents a neat frontal appearance.

With the above objects in view, and any others which may suggest themselves from the description to follow, a better understanding of the invention may be had by reference to the accompanying drawing, in which:

Fig. 1 is an elevation of the muffler as worn and fully closed;

Fig. 2 is an enlarged fragment of the muffler as seen from the rear side;

Fig. 3 is a similar view showing the muffler sections connected, and a portion of the muffler cloth removed to expose the bases of the slide fastener;

Fig. 4 is a section on the line 4-4 of Fig. 2; and Fig. 5 is a section on the line 5-5 of Fig. 3.

Mufflers or scarfs which contain a slide fastener closure are well known, and Fig. 3 of the E. Buchman patent, No. 2,042,442 of May 26, 1936 illustrates such a muffler. It is apparent from this figure and also from Fig. 4 of the patent that when the frontal sections of the muffler are connected by the slide fastener the inner edges of the sections are not in a closed or abutting relation, but somewhat spaced, exposing the metallic slide fastener. This construction has two disadvantages, one being that no cloth exists along the fastened course to protect the wearer from cold or other unpleasant weather conditions; and the other disadvantage is that the mechanical exposure of the slide fastener detracts from the neat or dressy appearance of the muffler. It has therefore been my intention to

correct these disadvantages and provide a muffler closure which attains all the objects outlined above.

In accordance with the foregoing, specific reference to the drawing indicates the top or neck-engaging portion of the muffler at 10 and the frontal sections thereof at 11. The familiar type of slide fastener is indicated at 15, each component thereof being carried by a cloth strip base 16. It is customary to sew the bases 16 on the cloth of any garment sections which are designed to be united by the fastener, and this is usually done along the back sides of the muffler sections 11 in the region where they are to be joined.

15 In the novel embodiment, the cloth of the muffler is given a special form in order to accommodate the slide fastener. To be specific, each frontal section 11 is first formed with a return fold 17 from its inner edge 18, such fold extending to a point where it is again returned as indicated at 18a along the rear side with a second fold 19 which terminates some distance short of the first edge 18. Here the fold 19 is again doubled back as indicated at 20 to form the rearmost 25 ply 21 of the muffler section.

The folds 17 and 19 are designed to be slightly spaced, whereby to form a pocket for the insertion of the corresponding cloth base 17 of the slide fastener 15. Now the entire folded and added stock of the section extends in a vertical course, and the assembly is finally made fast by stitching 30 22 to form a composite unit.

35 The unit just described places its component of the slide fastener 15 slightly beyond the frontal edge 18, as shown in Fig. 4; and with both sections identically formed, they may be joined by closing the fastener in the usual manner. When this is done, the edges 18 of the sections meet in abutting relation, as shown in Fig. 5, forming a closure of the cloth or other muffler material in the center thereof. In case it is found necessary or desirable, the cloth of the muffler sections may be formed with the edges 18 closer to the center than shown in Fig. 4, in which event a compressed 40 abutting closure or an overlapped one may be obtained.

45 It will be apparent that, with the muffler sections formed as described, the inner edges of the cloth are advanced, so to speak, toward each other to close and conceal the slide fastener when the latter is joined, lending the front of the muffler a neat appearance and providing an abutting or overlapped closure for the inner edges of the muffler sections to keep out the cold and other 50 unpleasant weather effects. Further, the frontal

portions of the muffler sections are not single plies, but folded or doubled ones. Coupled with similar sections, the latter form pockets for the slide fastener bases 16 which makes for a firm and sturdy center unit assembly when the units are stitched together and conceals the said base both on the front and back sides. Further, the unit plies combine not only to lend better body to the muffler front but also to provide added thickness for protection from cold or drafts. Finally, the novel closure has a neat appearance on both sides of the muffler sections, and improves the fit of the same.

While I have described the invention along specific lines, various minor changes or refinements may be made therein without departing from its principle, and I reserve the right to employ all such changes and refinements as may come within the scope and spirit of the appended claim.

I claim:

A scarf or muffler having oppositely disposed frontal sections including a slide fastener, each of said frontal sections comprising a main outer cloth facing section, said section being first folded back upon itself to form a folded edge portion, the cloth then being folded outwardly and rearwardly to form a pocket for the reception of the slide fastener, and a rear facing section, the outer edge of the rear facing section being spaced lat-

10
5

erally inwardly of the outer edge of the folded edge portion of the outer facing section, the slide fastener having a webbing adapted to be inserted within the pocket between the front and rear sections and vertical rows of stitching extending through both the front and rear sections to fasten the slide fastener and its webbing in place between the respective front and rear sections and further give stiffness to said frontal sections, the outer edges of the frontal sections abutting each other when the fastener is engaged.
